AUTOMATIC AUDIO TONE CONTROL
CIRCUITEdward W. Herold, Verona, N. Y., assignor to
Radio Corporation of America, a corporation
of Delaware

Application September 15, 1939, Serial No. 295,033

3 Claims. (Cl. 179—1)

My present invention relates generally to arrangements for automatically varying the audio frequency response characteristic of an audio transmission system, and more particularly to an improved method of, and means for, automatically varying the transmitted audio band width in response to the amplitude level variation of audio input energy.

Communication systems for the transmission, or reproduction, of audible sound are usually limited in volume range by background noise. It is well known that the annoyance caused by an audible fluctuation noise is greater when the noise contains the higher frequencies of the audible spectrum. This is true because, although the noise energy is uniformly distributed over the frequency spectrum, the useful sound energy is mainly concentrated in the lower frequencies. Thus, the highest effective signal to noise ratio in the presence of disturbing noise is usually obtained by cutting down the highest frequency which can be transmitted. Accordingly, the scratch noise present during playing of an ordinary phonograph record is less annoying when the reproduced audio frequency band does not extend above substantially 3,000 cycles. In high fidelity musical reproduction from records, this difficulty can only be overcome by recording at a sufficiently high level so that the weakest passages of music are sufficient to override the noise. This is not always possible, however, particularly when the music has loud passages which it is desired to reproduce without over-cutting the record. Similar limitations are found in other methods of reproduction.

Since the undesired noises are only annoying when the sound is at a low amplitude level, it is highly desirable to utilize an automatic means for reducing the band width of the reproduced audio frequency spectrum in accordance with the level of the desired sound. Hence, as long as the desired sound is at a high level the full frequency width of the audio system is in use for high fidelity reproduction. However, as soon as the desired sound energy decreases substantially to noise level, the width of the audio frequency spectrum should automatically be reduced to a value giving a higher effective signal to noise ratio. Low fidelity reproduction from such a system occurs only when the sound is at such a low amplitude level that enjoyable high fidelity reproduction is not possible because of noise; at all other times the full high fidelity capabilities of the audio system are utilized.

Accordingly, it may be stated that it is one of the main objects of my invention to provide an improved method of, and means for, automatically controlling the band width of the transmitted audio signals by a special regulating device whose function it is to adjust the frequency response at the high frequency end of the audio response characteristic, and to cause the frequency response adjustment to be a function of the amplitude of the sound at the input circuit of the audio transmission system.

Another important object of this invention is to provide an arrangement for improving the effective signal to noise ratio of the original sound source of an audio transmission system by means controlled directly by the sound waves and which opens up the audio frequency spectrum to the full width of which a sound transmission channel is capable when the level of desired sound energy is above a predetermined value which is sufficiently great substantially to eliminate annoyance from background noise; and the control additionally reduced the frequency spectrum to an extent sufficient such that undesired noises become less objectionable in the output of the gain transmission channel as soon as the desired sound amplitude level falls below a certain minimum and background noises becomes noticeably great.

Still other objects of this invention are to improve the operation of automatic arrangements for regulating the high audio frequency response of an audio signal transmission system, the control arrangement including an audio signal rectifier which functions to vary the gain of an electron discharge tube having circuits associated therewith to render it operative as a capacitive reactance across the audio transmission channel.

Still other objects of my invention are to improve generally automatic audio frequency response control circuits, and more especially to provide an audio signal transmission system with means for regulating the high audio response thereof, and which control means is reliable in operation and is economically assembled in an audio transmission system.

The novel features which I believe to be characteristic of my invention are set forth in particularity in the appended claims; the invention itself, however, as to both its organization and method of operation will best be understood by reference to the following description taken in connection with the drawing in which I have indicated diagrammatically a circuit organiza-

tion whereby my invention may be carried into effect.

In the drawing.

Fig. 1 shows a circuit diagram which embodies the invention.

Fig. 2 graphically shows the functioning of the audio response control circuit.

Referring now to Fig. 1, which shows an audio signal transmission channel embodying the automatic frequency response control circuit, numeral 1 denotes schematically a source of audio voltage. This audio voltage source may be of any well known type. For example, it may be the electrical pick-up device used in connection with reproducing phonograph records, or it may be the detector output circuit of a radio receiver of the broadcast type. It can even be the microphone of a public address system, or the photoelectric pick-up device used with talking moving pictures. In general, then, the source 1 is to be understood as feeding to the potentiometer resistor 2 audio signal voltage covering a range of approximately zero to 15,000 cycles, which latter range is generally considered as being the high fidelity audio reproduction range.

The numeral 4 denotes an audio amplifier tube of any well known type, and whose signal input grid 5 is connected by the adjustable tap 3 to the potentiometer resistor 2 shunted across the source of audio voltage 1. The cathode of tube 4 is connected to ground through the usual resistor-condenser grid biasing network 6. The screen grid of tube 4 has positive voltage applied to it through the usual resistor 7, the latter being by-passed to the cathode by a capacitor. The suppressor grid of tube 4 is at ground potential, while the plate 8 is established at a desired positive potential by the load resistor 9. Numeral 10 designates schematically a succeeding audio amplifier network, and the latter may comprise one or more audio amplifier tubes. The coupling condenser 11 transmits the audio voltage developed across load resistor 9 to the input electrode of amplifier 10.

The amplified audio voltage output of amplifier 10 may be impressed upon any desired utilization means, such as a reproducer of the loudspeaker type. The high audio frequency response of the audio response characteristic is automatically varied by the control channel which includes an amplifier 12. It is to be understood that this amplifier may include one or more amplifier tubes, or, if desired, the amplifier may be omitted. A desired value of audio signal voltage is impressed on amplifier 12 by providing in shunt with resistor 2 a resistor 13. The adjustable tap 14 enables the operator to select the desired magnitude of audio signal voltage which is to be employed for the control function. In other words, taps 3 and 14 provide independent means for permitting the regulation of the magnitudes of the input audio signal voltage and the control audio voltage. This is of decided advantage in providing increased flexibility of control.

The output of amplifier 12 is impressed upon a full wave rectifier which comprises the double diode tube 15 having a common cathode and a pair of anodes. One of the anodes 16 is connected to one end of the secondary winding of audio transformer 17, while the anode 18 is connected to the opposite end of the said winding. The grounded cathode of tube 15 is connected to the mid-point of the secondary winding through a load resistor 19 which is appropriately by-passed by condenser 20. The uni-directional voltage de-

veloped across resistor 19 is impressed on the input grid 21 of the control tube 22. The control voltage is impressed on grid 21 through a path which includes the filter resistor 23 and the grid leak resistor 24, and the junction of the resistors is grounded through a condenser 25. The resistors 19 and 23 and condensers 20 and 25 co-operate to provide a resistance-capacitance filter, and the time constant of this filter should be just long enough to prevent low frequency alternating voltage from being applied to the grid 21. In order to make the device operate as rapidly as possible a full wave rectifier is employed so that the time constant needed is only half that which would be required with a half wave rectifier. Of course, half wave rectification can be used in such cases where cost considerations make a slight sacrifice in performance desirable.

The tube 22 has circuits associated therewith such that the tube functions as an electronic capacitance. The plate 26 of the control tube is connected to the plate end of resistor 9 through a blocking condenser 27, while the cathode of the tube is connected to ground through the usual self-biasing resistor 28. The positive potential for plate 26 is applied through a path which includes the coil L and resistor R. A capacitance 29 is connected between grid 21 and the junction of resistor R and coil L, and the capacitance functions as a blocking condenser. Grid leak resistor 24 is a high resistance resistor. Considering the control tube 22 more specifically it is to be noted that the grid 21 is connected to plate 26 through the relatively high resistance R, while inductance L connects the control grid to the cathode. If an alternating voltage is applied across the plate to cathode path, and if resistor R is sufficiently high, a current will flow through R and L which is substantially in phase with the applied voltage. The voltage drop across coil L is applied to the grid 21 and is then leading the current (and thus the applied voltage) by approximately 90 degrees.

The resulting alternating current plate current due to this grid voltage will then lead the applied voltage by about 90 degrees. Assuming R is so high that the current through it can be neglected, the alternating voltage applied between plate and cathode of tube 22 results in a current across these electrodes which leads the voltage by approximately 90 degrees. In other words, the impedance between the plate and cathode of tube 22 functions in the manner of a capacitance, and the magnitude of this capacitance is proportional to the alternating plate current. Thus, when the transconductance of tube 22 is varied as by varying the bias of grid 21, the effective capacitance between the cathode and plate is varied. It can be demonstrated that a variation of the g_m of tube 22 will vary the effective capacitance provided by the impedance between the cathode and plate of tube 22 almost linearly, thus justifying the concept that the tube 22 behaves as a variable capacitance.

To use tube 22 for variable high frequency audio cut-off the plate to cathode impedance of the tube is connected across the resistive plate load 9 of amplifier tube 4. In Fig. 2 there is shown various frequency response curves secured with different values of transconductance for tube 22. In securing the various curves in Fig. 2 it was assumed that the resistive plate load of the amplifier 4 is of the order of 100,000 ohms, and in considering this magnitude the plate resistances of tubes 4 and 22 are to be included in this value.

The resistor R had a value of 200,000 ohms, while coil L had a value of 0.5 henry; it was considered that coil L had internal losses corresponding to a series resistor value of 200 ohms, and that g_m of tube 22 had a value of 2×10^{-3} mhos maximum. An inspection of the curves of Fig. 2 will show that the frequency response is varied from the uppermost flat curve, with a value of g_m which equals zero, to the lowermost curve which cuts off around 1,000 cycles. Also, it will be observed that the high audio frequency response depends directly on the transconductance of the tube 22. The control grid bias of tube 22 is varied without the consumption of power, and, therefore, represents a desirable manner of controlling the frequency response of the audio signal transmission channel.

In considering the operation of the circuit arrangement shown in Fig. 1, the audio input voltage is applied at the adjustable potentiometer 2-3 and the amplified audio voltage is transmitted to the utilization means as described above. The frequency response of the main transmission channel will be determined by the response characteristic of plate load resistor 9 and the shunt admittance connected across it by means of blocking condenser 27 and tube 22 and its associated components. The audio input signal is simultaneously applied to the adjustable potentiometer 13-14 which may be adjusted for selecting the scratch amplitude level which is desired to be tolerated. After amplification at amplifier 12 and rectification at double diode 15, the control voltage is applied to the grid 21 of the tube 22.

With noises, such as scratch noises, only impressed at the input network of the system, tap 14 is adjusted upwardly along resistor 13 until tube 22 just begins to decrease in plate current. Under these conditions tube 22 is operated at approximately maximum transconductance, and the response curve is similar to one of the lower curves shown in Fig. 2. The scratch components in the audio output of amplifier 10 are, therefore, less annoying because of the absence of high audio frequency components. When the audio signal amplitude exceeds the scratch, or noise, level slightly, the control grid 21 is biased more negatively and the response curve of the system approaches one of the higher curves of Fig. 2. For audio signal amplitudes well above the scratch level audio reproduction is in accordance with the uppermost curve of Fig. 2, since in that case tube 22 is completely cut-off. In this event full high fidelity reproduction is available. It will, therefore, be seen that the audio control channel provides a means for utilizing a uni-directional voltage derived from the audio signal itself, and which uni-directional voltage is employed to vary the gain of a tube whose plate to cathode impedance functions as a capacitance connected in shunt across the main audio signal transmission channel.

In some cases it may be advantageous to use a delayed bias on the double diode 15. Again, it is not essential to the present invention that the input to the control channel be derived from across source 1, since the input to the control channel may be taken from the plate resistor 9 or even from across the output of amplifier 10. Additionally, the variable electronic capacitance may be connected at other points of the transmission channel for varying the response characteristic.

It should, also, be pointed out that the opera-

tion shown by Fig. 2 is accompanied by a very slight volume expansion action. For low levels of the incoming sound, the relative maximum gain is slightly less than for high levels of the incoming sound. This behaviour is caused by the internal losses in the coil L together with the fact that the resistor R is not infinitely larger than the reactance of L. As a result the tube 22 and its accompanying circuit does not behave as a pure variable capacitance, but it also behaves as a variable conductance. The circuit values which were used for the illustrative curves of Fig. 2 were chosen, for simplicity, so that the volume expansion action was very small. By increasing L and decreasing R, or by inserting additional resistance in series with L, the volume expansion action may be made appreciable. Such behaviour is of advantage when the volume range of the incoming sound has been restricted, since it tends to restore the original volume range. The same action also tends to minimize noise and scratch which occur at low sound levels since not only is the frequency range reduced by the shunting capacitance action of tube 22, but the gain at all frequencies may be reduced by the shunt conductance action of the same tube.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In an audio transmission system of the type including at least one audio amplifier tube and a utilizing means, a frequency response control arrangement including an electron discharge tube having circuits associated therewith so as to render the plate to cathode impedance of the tube operable as a reactive impedance, means for connecting said reactive impedance across the output of said amplifier tube, and means connected across the amplifier tube input for deriving a uni-directional control voltage from audio voltage impressed upon said amplifier tube, and means for impressing said uni-directional voltage upon a control electrode of said control tube thereby to vary the magnitude of said reactive impedance.

2. In combination with a main audio voltage transmission channel, a control tube having its plate to cathode impedance connected across the channel to function as a shunt reactive path, and means connected across the main channel input and directly responsive to amplitude of the audio signal voltage impressed upon said main channel for controlling the gain of said control tube thereby to control the magnitude of said shunt reactive path.

3. In an audio voltage transmission system of the type including an audio amplifier having an input circuit and an output circuit, means for impressing audio signal voltage upon said input circuit, means connected to the amplifier input circuit for deriving a uni-directional control voltage from audio voltage transmitted through said audio transmission tube, a control tube provided with at least a cathode, output electrode and control grid, a connection between the output electrode of the control tube and said audio transmission system for impressing audio voltage between the cathode and output electrode

2,262,846

4. a vd beininqmocca et S .3111 vd sweda holt
of the control tube, means for developing an
alternating voltage component from said last
mentioned audio voltage and impressing it upon
the control grid of the control tube in quadrature
phase relation thereby to render the plate to
cathode impedance of the control tube operable
as a capacitance, and means for varying the gain
of the control tube in accordance with the
value of said capacitance which is as varied
thereby said last mentioned alternating voltage
is varied so as to maintain the ratio of the
currents in the control tube and the plate tube
constant, and means for varying the gain of the
control tube in accordance with the value of
the alternating voltage component developed
from the audio voltage and impressed upon
the control grid of the control tube.
